CLAIM

The ornamental design for a beverage cartridge, as shown and described.

DESCRIPTION

FIG. 1 is an upper perspective view of a beverage cartridge showing my new design;

FIG. 2 is a lower perspective view thereof;

FIG. 3 is top plan view thereof;

FIG. 4 is bottom plan view thereof; and,

FIG. 5 is a front side elevation view thereof, the rear side elevation view being identical.

The broken lines in the drawings depict portions of the beverage cartridge in which the design is embodied that form no part of the claimed design.
